NO. 11,503

UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR CARPET.

Specification forming part of Design No. **11,503**, dated November 11, 1879; application filed September 18, 1879.
[Term of patent 3½ years.]

To all whom it may concern:

Be it known that I, CHARLES MAGEE, of Brooklyn, Kings county, and State of New York, have invented a new and original Design for a Carpet, of which the following is a specification.

The accompanying photographic illustration represents a face view of my newly-designed carpet.

This invention relates to a new and original design for carpets, oil-cloths, and similar fabrics.

It consists of the new ornamentation and grouping of the figures hereinafter more fully described.

The groundwork of this carpet is divided into three fields or spaces, A, B, and C, of irregular shape, and without clearly-defined outline. The fields A, B, and C are to be of different color. The field C extends beneath both the fields A and B.

The carpet is ornamented by a multitude of small figures arranged upon the fields A B C. Several of these ornaments extend from one field into the other, and several form the boundaries between the fields. Thus the field A is ornamented by a rich floral group, a; the field B by another floral group, b, and by an

approximately octagonal figure, d, and a scroll, e. Another small octagonal figure, f, and a figure, g, having a triangular projection are placed at the junction of three fields, A B C. The field C is ornamented by a scroll, h, a rectangle, i, by floral embellishments, and various smaller figures.

I claim—

1. The design for a carpet, consisting of the fields A, B, and C, substantially as shown.
2. The design for a carpet, consisting of the field A, having group a, and field B, having group b and figures d e, substantially as shown.
3. The design for a carpet, consisting of the fields A B C and of the figures f g, substantially as shown.
4. The design for a carpet, consisting of the field C, having scroll h and square i, substantially as shown.
5. The design for a carpet, consisting of the field A, having group a, the field B, having group b and figures d e, the field C, having figures h i, and of the figures f and g, substantially as shown.

CHARLES MAGEE.
